[57] **CLAIM**

The ornamental design for a bracket for hanging vertical blinds, as shown and described.

DESCRIPTION

FIG. 1 is a front, right side perspective view of a bracket for hanging vertical blinds showing my new design;

FIG. 2 is a right side elevational view thereof, the left side being a mirror image of that shown;

FIG. 3 is a front elevational view thereof;

FIG. 4 is a rear elevational view thereof;

FIG. 5 is a bottom plan view thereof; and,

FIG. 6 is a top plan view thereof.

FIG. 1

FIG. 2

FIG. 3

FIG. 4

FIG. 5

FIG. 6
